UNITED STATES PATENT OFFICE.

JOHN H. BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,199,339.

Specification of Letters Patent. Patented Sept. 26, 1916.

Application filed November 24, 1915. Serial No. 63,251.

To all whom it may concern:

Be it known that I, JOHN H. BELL, a subject of the King of Great Britain, residing at East Orange, in the county of Essex and State of New Jersey, have invented certain new and useful Improvements in Telegraph Systems, of which the following is a full, clear, concise, and exact description.

10 This invention relates to telegraph systems of the double-current type, and its principal object is to provide an arrangement whereby a receiving operator may signal or "break" a transmitting operator at any time during the sending of messages. With the telegraph systems of this type at present in vogue, it is necessary for the receiving operator to wait until a sending operator has finished a message and throws his 15 key switch to receiving position or, as in some other systems, especially with repeaters, to wait for the pause in the transmission of signals to allow the restoration of the repeater apparatus before he can signal the sending operator. It may readily be that such a pause may not occur after each word, and the greater the number of words before a "break" can be made, the less easily can mistakes or uncertainties in sending or 20 receiving be remedied. By the application of this invention, however, the receiving operator can "break" at any time either on continuous or repeater lines, so that notification can be sent to the sending operator as 25 soon as incorrect, indistinct or questionable signals begin to arrive.

To this end the invention contemplates an arrangement whereby a signal at the transmitting station, adapted to operate according to the impulses transmitted, may be affected from a distant station, thus notifying the sending operator that a receiving operator wishes to use the line. The receiving apparatus at the transmitting station may 45 also be affected so that the operator may be given a double notification that the receiving operator is "breaking."

The above and other objects of this invention will be fully set forth in the following description and claims, and will be more readily understood by reference to the accompanying drawing, wherein—

Figure 1 shows diagrammatically the invention applied to a terminal station, Fig. 2

is a diagram of connections of a single repeater arranged in accordance with the invention, and Fig. 3 is a diagram of the connections of a forked repeater system.

In the so-called terminal stations of the transmission line, the character of the current impulses imparted thereto is governed by a transmitting relay 10, whose armature 11 is adapted to engage back and front contacts connected respectively to the negative and positive terminals of a suitable source 55 of energy, as indicated in Fig. 1. The incoming impulses from the line normally pass through the windings of a polarized relay 12, whose armature 13 is connected to a grounded source of energy 14. Armature 13 cooperates with a contact connected to the winding of a receiving signal, such as a grounded sounder 15. There is also provided the usual telegraph key 16 and a sending signal or sounder 17 located in a circuit 60 connected to one terminal of the winding of transmitting relay 10. If desired, sounders 15 and 17 and key 16 may be located at a subscriber's station removed some distance from the terminal station instead of at the terminal of a line section. The other terminal of the winding of relay 10 is connected to a terminal of the winding of a relay 20, the other terminal of which is connected to an armature 21 of a "break" 65 relay 22. Armature 21 cooperates with a back contact connected to a grounded source of energy 23. The line passes through the winding of relay 22 to an armature 24 of relay 20, this armature 24 operating with a 70 back contact connected to the winding of relay 12 and a front contact connected to armature 11. It will be apparent, therefore, that whenever key 16 is closed, a circuit is completed from ground through sounder 17, 75 relays 10 and 20, armature 21 and back contact of relay 22 to grounded source 23, whereupon relays 10 and 20 attract their armatures. Armature 24 of relay 20 connects armature 11 to the line through the 80 winding of relay 22, while armature 11 thereupon connects the line with the positive signal current supply. Relay 10 follows the subsequent opening and closing of key 16, so that the proper combinations of 85 positive and negative currents are transmitted to the line to form the desired signals. Relay 20, on the other hand, is a slow-re-

lease relay, attracting its armature readily upon the first passage of current through its winding, but thereafter not allowing its armature to become separated from its coöperating front contact during the comparatively short intervals between the signals making up the letters of a word. It may also readily be that in the case of rapid sending, relay 20 will not allow its armature 10 to fall back even during the intervals between words. Relay 22 is so constructed and adjusted that its armature 21 is not moved from engagement with its back contact by the normal strength of the signaling currents supplied through armature 11.

If two stations, similar to the terminal station shown in Fig. 1, are connected to the opposite ends of the transmission line without intervening repeaters, it will be apparent from the foregoing description that the closure of the sending key, corresponding to key 16, at the distant station (for convenience referred to as the receiving station) will there energize relays corresponding to transmitting relay 10 and slow release relay 20, whereupon positive current will be impressed upon the line from that station. If now, the key 16 is depressed, the relays 10 and 20 will be energized to move their respective armatures against their forward contact stops as already described, thereby disconnecting the receiving relay 12 and connecting the line relay 22 to the grounded source of positive current. When this condition occurs there will be times during the transmission of impulses at the sending station, when armature 11 at that station is against its back contact, and thereby connected to the grounded source of negative current. Therefore, since the two remote sources of grounded current supply will then be connected in series aiding, there will be a sufficient flow of current through relay 22 at the sending station to cause this relay to attract its armature 21. The attraction of armature 21 opens the previously traced circuit through relays 10 and 20, even though key 16 is at that instant closed, so that the outgoing signals registered on the sending sounder will be mutilated, such mutilation being easily detected by the experienced ear of an operator. The retraction of armature 24 extends the line through polarized relay 12, and if the key of the "breaking" operator is still depressed, armature 13 will cause the action of sounder 15, so that the sending operator will be notified that the receiving operator wishes the use of the line not only by the mutilation of the signals of his sending sounder, but by the intermittent operation of the receiving sounder. The subsequent retraction of armature 24 caused by the opening of the circuit 60 through relay 20 also disassociates armature

11 with the line, resulting in a decrease in the flow of current through relay 22, which thereupon releases its armature 21. If, now, the sending operator has ceased working his key, the receiving operator may signal 70 by causing the operation of relay 12 and sounder 15.

If a single repeater is interposed between the terminal stations, the connections are made according to Fig. 2. Line section 1 75 passes through the winding of a "break" relay 30 to an armature 31 of a slow-release relay 32, and from thence normally through the winding of a slow-release relay 33 to the winding of a polarized relay 34. 80 The other terminal of the winding of relay 34 is normally grounded through an armature 35 and a coöperating back contact of a "break" relay 36. In a similar manner, line section 2 passes through the winding 85 of "break" relay 36 to an armature 40 of slow-release relay 33, and from thence normally through a coöperating back contact of relay 33 through the winding of slow-release relay 32 to one terminal of the winding of a polarized relay 41. The other terminal of polarized relay 41 is normally grounded through an armature 42 and a coöperating back contact of "break" relay 30. Relay 34 is provided with an armature 95 45 connected to a front contact coöperating with armature 40 of relay 33, and is adapted to engage right-hand and left-hand contacts respectively connected to the positive and negative poles of a suitable source 100 of energy 46. The positive pole of source 46 is also connected to a front contact coöperating with armature 35 of "break" relay 36. Similarly, relay 41 is provided with an armature 47 connected to a front contact 105 coöperating with armature 31 of relay 32 and adapted to engage right-hand and left-hand contacts respectively connected to the positive and negative poles of a source of energy 48. The positive pole of the source 110 48 is also connected to a front contact coöperating with armature 42 of relay 30.

Signals, whose characters are determined by the positions of armature 11 of relay 10 of a terminal station arriving at the repeater over line section 1, pass through the winding of "break" relay 30, armature 31 and back contact of relay 32, through the windings of relay 33 and 34 and armature 35 and its coöperating back contact of relay 115 36 to ground. Relays 33 and 34 attract their armatures, armature 40, associating armature 45 with line section 2, through the winding of "break" relay 36; and armature 45 causing positive current from source 46 120 to flow over this circuit to a distant station preferably also arranged like Fig. 1, on line section 2. This current at the distant receiving station then passes through relays similar to "break" relay 22 and polarized 130

relay 12, causing the proper action of a receiving signal or sounder. Armature 45 follows all of the impulses arriving over line section 1, repeating those impulses to line section 2 by properly connecting the poles of source 46 thereto, as previously described, while slow-release relay 33 does not allow its armature 40 to become disengaged from its front contact during the reversals or low magnetic intervals between the impulses of a combination. "Break" relays 30 and 36 are so constructed that currents of normal strength, as supplied by a single terminal station, do not cause them to attract their armatures. If, now, the receiving operator wishes to "break" the sending operator, he depresses his sending key, causing positive current to be applied to the distant end of line section 2. Thereafter, as relay 34, characteristically following the incoming impulses from line section 1, connects armature 45 with the negative pole of source 46, this source is connected in series aiding to the source coöperating with armature 11, and an increased flow of current passes through the winding of "break" relay 36. This relay thereupon attracts its armature 35, completing a circuit from positive pole of source 6, through armature 35, windings of relays 34 and 33, back contact and armature 31 of relay 32, the winding of "break" relay 20 over line section 1, winding of "break" relay 22, armature 24 and front contact of relay 20, through armature 11 to the negative pole of the source of energy at the sending terminal station. There is therefore an increased flow of current through the windings of relays 30 and 22 which attract their armatures. The attraction of armature 42 of relay 30 performs no function at this time, but the attraction of armature 21 of relay 22 breaks the local sending circuit as hereinbefore described, resulting in the mutilation of the signals indicated by the sending sounder.

If the line conditions are such that relay 22 is energized for a sufficient period of time to open the circuit of slow-release relay 20 long enough for its armature 24 to fall back against its back contact, a circuit is completed through polarized relay 12 and the receiving signal or sounder will operate, giving a double indication that the distant operator has "broken" and wishes to use the line.

In case the distant operator is transmitting, the incoming impulses over line section 2 are repeated to line section 1 through the instrumentality of relays 32 and 41, and the operator at the terminal of line section 1 may "break" by depressing his key 16, which results in an increased flow of current through line section 2 because of the pulling up of "break" relay 30 in the following manner:

The attraction of armature 42 of relay 30

connects the positive pole of source 48 to line section 2 through the windings of relays 41 and 32, the back contact and armature 40 of relay 33 and the winding of relay 36. Thereafter, when the negative pole of source 70 of current at the distant station transmitting impulses over line section 2 is connected to this section by the opening of the sending key, the increased flow of current resulting therefrom will cause the energization of the 75 "break" relay 22 at the terminal station on line section 2, resulting in the mutilation of the signals of the sending sounder and producing intermittent signals on the receiving sounder, as hereinbefore explained in connection with Fig. 1.

In the forked repeater shown in Fig. 3, line section 1 is associated with a slow-release relay 50 having a pair of armatures 51 and 52, a "break" relay 53 provided with an armature 54 and a polarized relay 55 equipped with an armature 56. Armature 56 is connected to one terminal of the winding of relay 53 and coöperates with right-hand and left-hand contacts connected respectively to the positive and negative poles of a source of energy 57. Line section 2 is associated with a slow-release relay 60 having armatures 61 and 62, a "break" relay 63 having an armature 64 and a polarized relay 65 provided with an armature 66. Armature 66 is connected to one terminal of the winding of relay 63 and is adapted to engage right-hand and left-hand contacts respectively connected to the positive and negative terminals of the source of energy 67. In a like manner line section 3 is associated with a slow-release relay 70 having armatures 71 and 72, a "break" relay 73 having an armature 74, and a polarized relay 75 provided with an armature 76 being connected to relay 73 and coöperating with contacts connected to source 77. The impulses arriving over line section 1 pass through armature 72 and back contact of relay 70, armature 61 and back contact of relay 60 through the windings of relays 50 and 55 to ground at armature 54 of relay 53. Relays 50 and 55 attract their armatures, armature 51 connecting armature 56 115 to line section 2 through the winding of relay 53 and the back contact and armature 71 of relay 70, and armature 52 connecting armature 56 to line section 3 through the winding of relay 73 and the back contact 120 and armature 62 of relay 60. Armature 56 engaging its right-hand coöperating contact, therefore, connects the positive pole of source 57 to line sections 2 and 3. Subsequent impulses arriving over line section 1 125 are followed by polarized relay 55, which imparts to line sections 2 and 3 positive and negative currents corresponding to the impulses received over line section 1.

When the distant operator on either line 130

sections 2 or 3 desires to "break" the sending operator on line section 1, a source of energy is connected to that line section, preferably as previously described in connection with Fig. 1, and when during the operation of relay 55 following the impulses in line 1, source 57 and the source at the distant end of sections 2 or 3 are connected in series aiding, an increased flow of current passes 10 through "break" relay 53. Relay 53 thereupon attracts its armature 54, connecting the positive pole of source 57 to line section 1 over a path through the windings of relays 55 and 50, back contact and armature 15 61 of relay 60, and the back contact and armature 72 of relay 70. When the manipulation of the sending key at the terminal station on line section 1 connects the source of sending current in series aiding with 20 source 57, there is an increased flow of current through the winding of the "break" relay 22 at that terminal station, which mutilates the signals of the sending sounder and causes intermittent operations of the receiving sounder, as previously described. In a similar manner, impulses arriving over line section 2 are repeated to line sections 1 and 3, and the sending operator on section 2 may be "broken" by the receiving operators at 25 30 the terminal stations on either of the other sections, and impulses arriving over line section 3 may be repeated to line sections 1 and 2, and the sending operator on section 3 may be "broken" by the receiving operators on sections 1 and 2.

What is claimed is:

1. In a telegraph system, a main line circuit and telegraphic transmitting and receiving means therefor, and a line relay normally inoperative under telegraphic signals 40 for operatively controlling said transmitting means.

2. In a telegraph system, a main line circuit and a plurality of transmitting and receiving equipments therefor, a plurality of 45 line relays unresponsive to telegraphic signals for operatively controlling said transmitting equipments, and means responsive on the simultaneous operation of more than one of said transmitting equipments to cause 50 the actuation of said line relays to interfere with said transmitting equipments.

3. A telegraph system comprising a transmission line, transmitting means at one station on said line to impart signal current 55 impulses thereover to a distant station, a signal at the transmitting station controlled by and adapted to operate according to the impulses so transmitted, and a relay also at the transmitting station traversed 60 but unaffected by such current impulses but affected by increased currents for affecting the operation of said signal, and means located at a distant station for increasing the flow of current through said relay to effect 65 its operation.

In witness whereof, I hereunto subscribe my name this 20th day of November, A. D., 1915.

JOHN H. BELL.
